UNITED STATES PATENT OFFICE.

JAMES T. COWLEY, OF SYRACUSE, NEW YORK, ASSIGNOR TO THE LAMSON COMPANY, OF BOSTON, MASSACHUSETTS, A CORPORATION OF MASSACHUSETTS.

PRESSURE-CONTROL MECHANISM FOR PNEUMATIC-DISPATCH SYSTEMS.

Application filed November 3, 1922. Serial No. 598,877.

This invention pertains to power control mechanism for use in pneumatic dispatch system and relates more specifically to that type of power controller which is automatically set into operation by the variation in pressure in the transmission tube incident to the introduction of a carrier therein. In pneumatic dispatch systems of the vacuum or low pressure type a slight negative pressure is constantly maintained in the transmission tube and upon the introduction of a carrier the pressure within the tube in front of the carrier is further slightly decreased due to the drag or inertia of the carrier. This lowering of the pressure is commonly depended upon to initiate the operation of means for opening a valve in a passage connecting the transmission tube with a chamber in which a relatively high vacuum is maintained, thus suddenly lowering the pressure in the transmission tube and producing a suction therein sufficient to move the carrier rapidly toward the discharge end. Upon delivery of the carrier, it is desirable immediately to restore the pressure conditions in the tube substantially to normal in order to permit the operation to be repeated, but as the valve controlling means is sensitive to even a small decrease in pressure below normal in the transmission tube and as the pressure in such tube at the time of delivery of the carrier is still far below the normal pressure, it is evident that some additional device must be employed to assure closing of the valve. In some instances timing devices have been employed so arranged as to close the valve after a predetermined time interval irrespective of the position of the carrier, but such devices are not as economical of power as might be desired, as the valve may remain open a considerable time after the carrier has been discharged from the tube, either by reason of an unusually rapid passage of the carrier, or on account of the necessity of a second opening of the valve to complete the transmission of the carrier, such second opening taking place perhaps just prior to discharge of the carrier. The principal object of the present invention is to provide power controlling means useful in pneumatic dispatch systems and more especially systems of the low pressure or vacuum type such as above referred to of such character that while sensitively responsive to the slight decrease in

pressure in the transmission tube resulting from the introduction of a carrier therein, it will be equally responsive to the slight increase in pressure in the tube incident to the delivery of the carrier therefrom, thereby assuring the prompt closing of the valve and the restoration of normal pressure conditions in the transmission tube immediately after discharge of the carrier from the tube.

In accomplishing the above objects, the pressure valve is preferably actuated by a pneumatic motor of usual type having a chamber which normally communicates freely with the transmission tube so that variations in pressure are quickly equalized in the tube and chamber, all in usual manner. In accordance with the present invention, provision is made for cutting off such free communication between the motor chamber and tube immediately upon the occurrence of the sudden drop in pressure in the tube incident to the opening of the main pressure valve, and so long as such minimum pressure in the transmission tube continues, the pressure in the motor chamber is kept substantially constant and slightly below normal pressure by permitting the withdrawal from and admission to the motor chamber of substantially equal and regulable quantities of air through restricted passages leading to the transmission tube and the atmosphere, respectively. Upon slight increase in pressure in the transmission tube due to discharge of the carrier, the rate of withdrawal of air from the motor chamber is thereby decreased, permitting pressure in such chamber to rise to normal, whereupon the main pressure valve is closed, restoring the parts to original position.

In the accompanying drawings one embodiment of the invention is illustrated by way of example and in such drawings:

Fig. 1 is a fragmentary side elevation of a portion of a pneumatic dispatch tube system showing the present power controlling device as applied thereto;

Fig. 2 is a vertical diametrical cross section through the power controlling device on a line such as 2-2 of Fig. 3 and to a larger scale than Fig. 1;

Fig. 3 is a plan view of the device shown in Fig. 2;

Fig. 4 is a vertical cross section on a line such as 4-4 of Fig. 3 and to a somewhat larger scale; and

Fig. 5 is a fragmentary vertical cross section upon the same plane as Fig. 2 and showing the parts as occupying a different position from that of Fig. 2.

Referring to the drawings, the numeral 1 indicates a portion of a central station desk and the numeral 2 designates one of the several carrier transmission tubes which extend from the various sub-stations to the central station. This tube is provided in the usual manner with a discharge terminal 3 normally closed by a valve 4 and is continued as indicated at 5 beyond the discharge terminal and ends in a substantially horizontal portion 5^a providing a chamber 6 and constituting a part of the casing or housing of the controlling device hereinafter more fully described. The usual vacuum drum is indicated at 7. A suction pipe or tube 8 is connected at one end to this drum while its other end terminates in the part 9 constituting a portion of the casing of the controlling device. The inner end of the chamber 6 projects transversely into a chamber 10 within the part 9. The projecting end of chamber 6 has opposed walls 11, 12 provided with openings in which fit the heads 13 and 14 respectively of a balanced main pressure valve 15. Preferably the head 14 of this valve is furnished with guide fins 16 for centering it within its opening when the valve is open. A port 17 of relatively small area provides communication between chamber 6 and the chamber 10. If desired this port may be omitted and one or the other of the valve heads, as for example the valve head 13, may be made to fit somewhat loosely in the corresponding opening whereby to provide an annular port 18 connecting the chamber 6 with the chamber 10. If desired both the port 17 and the port 18 may be employed.

The valve 15 is provided with a stem 19 which passes up through and is guided within a bore in a plate or cover 20 secured in an opening in the partition wall 21 extending transversely across the casing or housing. This partition wall is of dished form having the rim portion 22 to which the peripheral portion 23 of a cover member 24 is secured by means of screws 25. The edges of a flexible diaphragm 26 are clamped between the members 22 and 23. This diaphragm forms a movable wall for the motor chamber 27 thus provided between the diaphragm and the cover member 24. The opposite side of the diaphragm is always exposed to atmospheric pressure by the provision of a port 28 in the outer portion of the partition 21. The valve stem 19 passes up through the central part of the diaphragm and the latter is clamped between a pair of washers 29, 30, respectively, which are secured to the stem 19 by means of a nut 31.

The central part of the cover 24 is fur-

nished with an upstanding boss 32 having an internally screw threaded bore 33 in which a gland 34 is adjustably mounted. This gland is provided with a central bore forming a guide for a slideable auxiliary stem member 35 arranged in alignment with the stem 19. The lower end of this stem member 35 is reduced in diameter and screw threaded for the reception of a nut 36. A yoke member 37 is clamped between the nut 36 and a shoulder at the lower end of the stem member 35 and a coiled spring 38 surrounds the stem member 35, bearing at one end against the yoke and being received at its other end within a socket 39 in the gland 34. The cover member 24 is provided with a passage 40 opening at 41 into the chamber 6 and at its other end through the port 42 into the chamber 27. A second port 43 of much smaller area than the port 42 also connects the passage 40 with the chamber 27 and this port 43 may be controlled by means of an adjustable needle valve 44 of usual type. The cover 24 is also provided with a passage 45 opening to the atmosphere at one end and leading by means of a port 46 at its other end into the chamber 27. This port may also be regulated by means of a needle valve 48 of usual type. Preferably another passage 49 (Fig. 4) leads from the atmosphere to a port 50 opening into the chamber 27, and this port is also controlled by a needle valve 51.

A bracket 52 is secured to the inner side of the cover 24 and this bracket is provided with a fulcrum pin 55 upon which a lever 56 is supported. This lever has an opening for the passage of the stem 35 and is provided at one end with a valve disk 58 cooperable with the port 46 for closing the latter and at its other end with a valve disk 57 cooperable with the port 42. A pair of springs 59, 60 are secured to the lever 56 adjacent to that end thereof having the valve disk 57. The opposite ends of these springs are secured respectively to brackets 61, 62 forming parts of the yoke member 37. The stem 19 and the auxiliary stem member 35 are provided with aligned bores in which the opposite ends of a pin 63 are received, such pin serving to maintain the members 19 and 35 in alignment.

The parts normally occupy the position shown in Fig. 2 wherein the port 42 is wide open and port 46 is entirely closed, the diaphragm occupying its lowermost position and communication between the chambers 6 and 10 being substantially cut off except through the ports 17 and 18. When the parts are thus disposed, the low pressure maintained in the chamber 7 results in a slight but constant flow of air through the transmission tube in the direction of the arrow A in Fig. 2, the pressure in such tube being thus maintained very slightly below

atmospheric pressure. When a carrier is placed in the tube the pressure in front of the carrier drops slightly due to the inertia and frictional resistance to movement of the carrier, and thus the pressure in the motor chamber 27 is further slightly decreased thereby causing the diaphragm to rise. This opens main pressure valve 15 so that free communication is provided between the vacuum drum and the transmission tube. The pressure in the latter immediately drops to a relatively low point producing a strong suction in the tube which causes the carrier to travel rapidly toward its discharge end. As the valve 15 rises, the points of connection of the springs 59, 60 with the yoke member 37 also rise as shown in Fig. 5 until they pass the horizontal plane of the fulcrum pin 55. The springs thereupon immediately snap the lever 56 into the position shown in Fig. 5 wherein the port 42 is closed and the port 46 opened. The closing of the port 42 cuts off communication between the motor chamber 27 and the transmission tube except for the restricted passage provided by the port 43. The only air which can now be drawn from the chamber 27 by the relatively high suction in the chamber 6 must bleed through this restricted port 43, and the needle valves 44 and 48 are so adjusted that the air passing out through the port 43 is substantially compensated for by air which bleeds in through the channel 45 and the now open port 46. The pressure in chamber 27 is thus maintained substantially the same as that which existed therein at the instant of upward movement of the diaphragm, even though the pressure in the chamber 6 is very much lower and the diaphragm thus remains in its upper position holding the valve 15 open. After the closing of valve 57, the difference in pressure upon its opposite sides assists the springs 59, 60 in keeping it closed.

When the pressure in the transmission tube rises slightly above the transmission pressure, for example by reason of delivery of the carrier from the tube, the suction in the chamber 6 decreases slightly so that the quantity of air drawn through the port 43 also decreases. As the air passage through the port 46 remains unchanged, pressure immediately builds up in chamber 27 until the weight of the parts or the spring 38 acts to restore the diaphragm to its normal position. As the diaphragm moves down the valve 15 is closed, but the independence of the stem members 19 and 35 permits the opening of the port 42 to be slightly delayed. This delay is due partly to the arrangement of the springs 59 and 60 which must be restored substantially to the position of Fig. 2 before the valve 57 is affected thereby and partly by the differences in pressure upon the opposite sides of the valve. This delay

serves to insure the complete closure of the main valve 15 before the port 42 is uncovered, this being necessary as otherwise the main valve would immediately open again. With this arrangement accurate timing or 70 relative adjustment of the parts is made unnecessary.

If a second carrier were introduced into the tube prior to the discharge of the first, the pressure in the tube will not substantially rise upon the discharge of the first carrier so that the diaphragm and the valve 15 will remain in the position shown in Fig. 5 until the discharge of the second carrier. The needle valve 51 with its port 50 permits 80 a small amount of air to bleed into the chamber 27 under normal conditions so that there is no tendency to decrease the pressure in the motor chamber beyond the normal amount prior to the introduction of a carrier into the tube. This needle valve permits a small quantity of air to enter the chamber 27 even when the valve 57 is closed, but the adjustment of the needle valve 48 is made such as to compensate for air leaking through the valve port 50.

The arrangement above described provides efficient and economical means for controlling the application of power to the system and dispenses with the employment of 95 controlling valve mechanism or similar devices at the several sending stations. It also assures the closing of the main valve immediately upon the discharge of the last carrier in the tube so that there is no substantial loss of energy and the system is immediately restored to normal condition after the completion of each operation. While a specific arrangement of parts has herein been shown, it is to be understood that the embodiment herein shown is illustrative only of the various embodiments of means whereby the invention might readily be carried into effect.

I claim:

1. Power controlling apparatus for pneumatic dispatch systems comprising an air conduit, a valve controlling the flow of air through said conduit, a pneumatic for actuating the valve, one side of said pneumatic being freely exposed at all times to atmospheric pressure and the other side thereof normally being exposed to the pressure obtaining in the conduit to one side of the valve, and means for restricting communication between the conduit and the latter side of the pneumatic comprising a normally open auxiliary valve and a spring alternatively operative to hold the auxiliary valve in open or closed position respectively.

2. Pneumatic dispatch apparatus having a transmission tube, an exhauster connected therewith, a valve for controlling the flow of carrier propelling air current through the transmission tube, a minimum flow of air

through the tube being permitted when the valve is in closed position, and a pneumatic for operating the valve, one side of the pneumatic being exposed freely at all times to atmospheric pressure, means for determining the effective pressure acting upon the opposite side of the pneumatic, an auxiliary valve controlling a passage leading from the transmission tube, a spring normally holding said valve open, and means connecting the spring to the pneumatic so constructed and arranged that upon movement of the pneumatic from normal position the spring is so stressed as to close said auxiliary valve.

15. 3. Pneumatic dispatch apparatus having a transmission tube, an exhauster connected therewith, a valve for controlling the flow of carrier propelling air current through the transmission tube, a minimum flow of air through the tube being permitted when the valve is in closed position, and a pneumatic for operating the valve, one side of the pneumatic being exposed freely at all times to atmospheric pressure, a normally open pivotally supported auxiliary valve for controlling a passage leading from the transmission tube to the opposite side of the pneumatic, and spring means operative alternatively in accordance with the position of the pneumatic to hold said auxiliary valve open or closed respectively.

40. 4. Pneumatic dispatch apparatus having a transmission tube, an exhauster connected therewith, a valve for controlling the flow of carrier propelling air current through the transmission tube, a minimum flow of air through the tube being permitted when the valve is in closed position, and a pneumatic for operating the valve, one side of the pneumatic being exposed freely at all times to atmospheric pressure, a pivoted lever, a normally open auxiliary valve carried by the lever, said auxiliary valve controlling a passage leading from the transmission tube to the opposite side of the pneumatic, a spring having one end secured to the lever, said spring normally being so stressed as to hold the valve open, and means actuated by the pneumatic for shifting the other end of the spring whereby to close the auxiliary valve.

45. 5. Power control apparatus comprising in combination with a transmission tube and a suction tube, a valve for controlling communication between said tubes, a pneumatic motor having a chamber provided with a movable wall connected with the valve, ports connecting the said chamber with the transmission tube and with the outer air, means normally closing the latter port, and means operative upon movement of the movable wall of the chamber in one direction for opening the port leading to the outer air and closing the port leading to the transmission tube.

60. 6. Power control apparatus for use with

a pneumatic transmission tube, a suction tube, and a valve controlling communication therebetween, comprising a pneumatic motor having a chamber provided with a movable wall connected with the valve, a restricted port connecting said chamber with the outer air, a relatively large port connecting the chamber with the transmission tube, and valve means for alternatively closing one of said ports and opening the other.

70. 7. Power control apparatus of the class described comprising a pneumatic motor having a chamber provided with a movable side wall, means connecting said chamber with a space in which the air pressure fluctuates, said means comprising a relatively small port of adjustable capacity and a larger, normally unobstructed port, a regulable port of small capacity connecting the chamber with the atmosphere, a valve normally closing said latter port, a second valve operable to close the large port, and means actuable by inward movement of said movable wall to open said first valve and close the second valve.

75. 8. Power control apparatus comprising a pneumatic motor having a chamber closed at one side by a movable diaphragm, the diaphragm having a sliding stem, a pair of ports opening into the chamber, a lever fulcrumed within the chamber, said lever having an opening for the passage of the sliding stem of the diaphragm, a valve member carried upon each end of the lever, said valve members being constructed and arranged alternately to close the respective ports, and connections between the diaphragm and lever for actuating the latter.

80. 9. Power control apparatus comprising a valve and a pneumatic motor for actuating it, said motor having a chamber, a diaphragm forming one wall thereof, a port leading from the chamber to the atmosphere, a second port leading from the chamber to a space in which the pressure fluctuates, a valve for closing each of said ports, one of said valves being open when the other is closed, and means comprising a resilient element for suddenly changing the relative positions of said valve upon movement of the diaphragm in either direction, the port leading to the atmosphere normally being closed by its valve.

85. 10. A power controlling apparatus comprising a main valve and a pneumatic motor for actuating it, said motor having a chamber closed at one side by a diaphragm, a stem connecting the main valve with the diaphragm and projecting into the chamber, a valve for determining the admission of atmospheric air to the chamber, a spring normally positioned to hold said latter valve closed, and means connecting said spring with the valve stem so constructed and arranged that upon movement of the dia-

phragm from normal position the spring is so stressed as to open the air admission valve.

11. A power controlling apparatus comprising a valve having a stem and a pneumatic motor for actuating the valve, said motor having a chamber closed at one side by a diaphragm, means connecting the valve stem to the diaphragm, a pair of ports for determining pressure conditions in said chamber, one of said ports opening to the atmosphere, valves for closing said ports, means so connecting said valves that when one is open the other is closed, and spring means operative alternatively, in accordance with the position of the diaphragm, for holding one of said valves either in open or closed position, the valve associated with the port leading to the atmosphere normally being closed.

12. A pneumatic motor for use in pneumatic systems comprising a housing having a chamber therein, a diaphragm forming one wall of said chamber, a pair of ports opening into the chamber, a lever fulcrumed within the chamber, valves mounted upon opposite ends of the lever and cooperable with the respective ports, a spring having one end secured to the lever normally arranged to hold one of said valves in closed position, and means moving with the diaphragm for so shifting said spring as to cause the other valve to be closed and the first valve to be opened.

13. A pneumatic motor for use in pneumatic conveyor systems comprising a housing having a chamber provided with a movable wall, a port leading from the chamber to the atmosphere, a movable valve cooperating with the port, and a spring interposed between the valve and movable wall and so constructed and arranged that as the movable wall approaches its limit of movement in either direction the valve is moved suddenly from one extreme position to the other, the valve being normally positioned to close the port leading to the atmosphere.

14. A pneumatic motor for use in pneumatic conveyor systems comprising a housing having a chamber therein, a diaphragm forming one wall of the housing, a pair of ports for controlling pressure conditions within the chamber, a lever pivoted within the chamber carrying a valve member at

either end, said valve members cooperating with the respective ports, a spring having one end connected to the lever and the other end connected with the diaphragm, said latter end being movable upon movement of the diaphragm from a position at one side of the fulcrum of the lever to a position at the other side of said fulcrum whereby suddenly to swing the lever from one extreme position to the other.

15. Power control apparatus comprising a pneumatic motor having a chamber and a diaphragm forming one wall thereof, a valve controlled passage connecting said chamber with a space in which a negative and fluctuating air pressure is maintained, a valve controlled passage of relatively small capacity connecting the chamber with the outer air, and a pair of simultaneously movable valves for controlling said passages, said valves being actuatable by the diaphragm.

16. A pneumatic motor for use in pneumatic dispatch systems comprising a housing having a chamber closed at one side by a diaphragm, a pair of ports provided with needle valves opening into the chamber, a valve normally completely closing one of said ports, and means connecting said last named valve with the diaphragm whereby upon movement of the latter said valve is moved to uncover its port.

17. A pneumatic motor for a carrier dispatch system comprising a housing having a chamber therein closed at one side by a movable diaphragm, a pair of ports connecting said chamber with the outer atmosphere, said ports being provided with needle valves, a valve member normally completely closing one of said ports, a second pair of ports opening into said chamber and connecting with a low pressure space, one of said latter ports being provided with a needle valve and the other being normally open and of relatively large capacity, a valve member for completely closing such larger port, means connecting said valve members for simultaneous but opposite movement toward and from the ports with which they cooperate, and means connecting said valve members with the diaphragm for actuation thereby.

Signed by me at Syracuse, New York this 29th day of September, 1922.

JAMES T. COWLEY.
